UNITED STATES PATENT OFFICE.

JOHN H. FOOTE, OF DAYTON, OHIO.

DESIGN FOR A PENHOLDER-RACK.

43,873.

Specification for Design.

Patented Apr. 22, 1913.

Application filed January 6, 1913. Serial No. 740,549. Term of patent 7 years.

To all whom it may concern:

Be it known that I, JOHN H. FOOTE, a citizen of the United States, residing at Dayton, in the county of Montgomery and State of Ohio, (post-office address National Military Home, Dayton, Ohio,) have invented a new, original, and ornamental Design for a Penholder-Rack, of which the following is a specification, reference being had to the accompanying drawings, forming a part hereof.

Figure 1 is a top plan of a pen holder rack, showing my new design. Fig. 2 is a front view of the same, and Fig. 3, is a side elevation thereof.

I claim;

The ornamental design for a pen holder rack, as shown.

JOHN H. FOOTE.

Witnesses:

R. J. McCARTY,
MATTHEW SIEBLER.
